UNITED STATES PATENT OFFICE.

JOHN H. ANDERSON, OF JONES' VALLEY, TENNESSEE.

HARROW.

SPECIFICATION forming part of Letters Patent No. 349,557, dated September 21, 1886.

Application filed June 28, 1886. Serial No. 206,421. (No model.)

To all whom it may concern:

Be it known that I, JOHN H. ANDERSON, a citizen of the United States, and a resident of Jones' Valley, in the county of Hickman and State of Tennessee, have invented certain new and useful Improvements in Harrows; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved reversible harrow. Fig. 2 is a longitudinal vertical sectional view of the same. Fig. 3 is a top view, and Fig. 4 is a bottom view.

Similar letters of reference indicate corresponding parts in all the figures.

20 My invention has relation to that class of harrows in which a number of teeth are secured to a beam, which is pivoted at its middle, and provided with means for adjusting it at different angles to the draft-beam; and it 25 consists in the improved construction and combination of parts of the same, as hereinafter more fully described and claimed.

In the accompanying drawings, the letter A indicates the beam, to the forward end of which 30 the draft is attached. Inclined handles B B are secured to the beam, and have a cross-piece, C, which connects them and passes through the upper end of an upright, D, upon the rear end of the beam. A metallic strap, 35 E, is secured to the under side of the beam, and the rear end of this strap is bent downward and rearward to form a perforated lip, F, between which and the under side of the beam the transverse harrow-beam G is pivoted upon 40 a bolt, H, passing through the lip, transverse harrow-beam, and the draft-beam, the lower end of the said bolt forming a tooth, I, similar in construction to the other teeth, J, of the harrow-beam. A semicircular bar, K, is secured 45 at its ends to the ends of the harrow-beam, projecting forward and sliding under the beam in a recess, L, in the same between the beam and the strap, and the forward central portion of this semicircular bar is formed with a number 50 of perforations, M, which register with a cor-

responding perforation, N, in the beam and in the strap. A bolt, O, is secured to the forward free end of a flat spring, P, secured at its rear end upon the upper side of the rear end of the beam, and this bolt is held by the spring into 55 the perforation in the beam, entering the perforations in the bar when they are brought to register with it. A lever, Q, is pivoted upon the side of the upright at the rear end of the beam, and has a link, R, at its forward end, 60 pivoted to the flat spring, while its rear end is bent downward and to one side, forming a treadle, S, by means of which the rear end of the lever may be depressed with the foot of the person guiding the harrow by the handles. 65

It will be seen that when the treadle end of the lever is depressed the bolt will be raised and the semicircular bar may slide freely in its guide formed by the recess in the under side of the beam and by the strap, allowing 70 the beam to be tilted at any desired angle to the draft-beam, and when the harrow-beam has arrived to its desired angle the perforation registering with the perforation in the beam will admit of the bolt being forced down 75 by the flat spring. This will adapt the harrow to be used on hillsides and similar inclined ground, as the harrow will be capable of throwing the soil downhill when going in either direction, and the harrow will also be useful 80 in cultivating between rows of plants, when it may be adjusted to throw the soil toward the rows or from the rows, as desired.

Having thus described my invention, I claim and desire to secure by Letters Patent of the 85 United States—

1. In a harrow, the combination of a draft-beam having handles, a harrow-beam pivoted at its middle under the rear portion of the draft-beam, and having a semicircular bar projecting forward and formed with perforations, and a bolt fitting in a perforation in the draft-beam registering with the perforations in the semicircular bar, and having a spring for forcing it down and a foot-lever for raising it, as 95 and for the purpose shown and set forth.

2. In a harrow, the combination of a draft-beam, a harrow-beam pivotally secured thereto, and having a forwardly-projecting perforated semicircular bar, a spring secured at one 100

end to said draft-beam, and having a pin and a link secured to its free end, and a lever pivotally secured to the rear of said harrow, the forward end of which is secured to said link, 5 and its rear end is bent downwardly and to one side to form a treadle.

In testimony that I claim the foregoing as

my own I have hereunto affixed my signature in presence of two witnesses.

JOHN H. ANDERSON.
